UNITED STATES PATENT OFFICE.

JOSEPH HETHERINGTON STUBBS, OF ANCOATS, MANCHESTER, ENGLAND, ASSIGNOR TO
JOSEPH STUBBS LIMITED, OF MANCHESTER, ENGLAND, A LIMITED LIABILITY
COMPANY OF GREAT BRITAIN.

STOP MOTION FOR WINDING AND ANALOGOUS MACHINES.

Application filed December 24, 1925, Serial No. 77,595, and in Great Britain October 1, 1925.

The application to winding machines for the winding of artificial silk, of stop motions as generally applied to machines for winding cotton and woolen and other twisted 5 yarns, is not practicable, as the artificial silk during winding, in the earlier stages of its production, is in such a condition that it will not bear any weight or suffer any bending or angles in the length of yarn.

10 The present invention has for object a very simple and efficient stop motion to be applied to an apparatus for winding artificial silk yarns, without damage to the yarn.

15 The invention will now be described fully with reference to the accompanying drawings, wherein Figure 1 is a side elevation of a swift having wound upon it artificial silk yarns and showing the feeler which according to the invention actuates the knock 20 off motion; Figure 2 being a front elevation of the feeler and its support with a type of knock off motion which may be actuated thereby.

25 In the drawings, yarn passes from a yarn package below (not shown) for instance a cake as it comes from a spinning box in the viscose process, thence through eye 3 to eye 4 on the usual yarn traversing arm 5, and thence to and around the rotating swift 6. 30 All of these parts are known, and need not be described here.

35 Between the eyes 3 and 4 is mounted the feeler 7, of wire which wire is returned at its lower end and bears on such returned portion the rotating flanged spindle or bobbin 8 of ebonite or like material. The upper end of the feeler is bent round and has screwed to it the plate 9, and the whole feeler unit thus formed is pivotally mounted in a frame 40 or carrier 10 supported on the frame 11 of the machine as shown. The yarn α passes between two faces 12—Figure 2—which serve to limit in its traversing motion under the influences of traverse arm 5.

45 The feeler 7 according to my invention is in actual operative position at a slight angle to the vertical as shown, that is to say, it is substantially parallel to the yarn α as it passes from eye 3 to 4. As a result of 50 this arrangement, the weight on either side of the pivot 13 may be so arranged including the plate 9, that the upper portion is a shade the heavier, just sufficient to allow the feeler

to have motion by gravity around 13 when the yarn α breaks or is removed.

55 The method illustrated of operating the knock off motion from this fall of the upper end of the feeler around its pivot 13 will now be described. 14 is a wiper shaft with wipers 15 and this shaft is rotated from a 60 chain wheel 16, Figure 2, through chain 17 and sprocket wheel 18, and which wheel is loose on the shaft 14. This wheel however has formed solid with it the collar 19 with groove 20 and an inclined face 21 which 65 latter abuts against an inclined face 22 on a driving block or collar 23 fast on the shaft 14. A pressure spring 24, abutting at one end against a collar 25 pinned on shaft 14, and at the other end against the inner end of 70 the tubular boss 19 on sprocket wheel 18, serves to maintain tight driving contact between the inclined faces of members 19 and 23.

75 When the yarn α breaks the upper end of feeler 7 swings downwardly and the plate 9 thus comes into the path of a wiper 15 on the shaft 14. The rotation of the said shaft and therefore of the driving member 23 fast thereon being thus arrested, the sprocket 80 wheel 18 and member 19 are pushed to the left along the shaft 14, by the rotation of sprocket 18, inclined face 21 of member 19 forcing this movement by its sliding contact with the now stationary member 23. A 85 lever 26 the end of which engages in groove 20 and which lever is fulcrumed in a bracket 27, presses with its upper cranked end against an arm 28 as a result of this movement of the parts along the shaft 14. 90 The arm 28 is pivoted at 29 to the machine frame 11 and is supported at its upper end in a slotted lug 30. The arm 28 moves against the pressure of a plate spring 31 and in so moving brings a detent 32 from beneath a 95 cranked member 33 which the said detent normally supports to keep the spur wheel 34 in positive engagement with a further driving spur wheel—not shown. The spur wheel 35 shown in the drawings is driven 100 from the spur wheel 34 and actuates the usual well known counting mechanism, which is not further shown or described. As a result of the removal of the detent 32 as 105 stated the dropping of the support 33 has the result therefore that spur wheel 34 rolls

on the counting gear spur wheel 35 and out of mesh with the driving spur wheel, the swift and counting mechanism thus being stopped simultaneously as a result of the 5 movement of the feeler 7.

The breakage of yarn having been repaired, the parts are again fixed in their original positions and the drive recommences. To avoid possible damage to the 10 feeler 7 and for the convenience of the operative, lever 36 is provided having a short spindle 37 at the end thereof to come under the upper end of the feeler wire, when the handle 38 of the lever is depressed; this lever 15 is pivoted at 39.

As will be understood, any knock off motion may be employed which can be operated by the arresting of a rotating member through the fall of the feeler 7. Also, the 20 configuration of the said feeler may be altered as may be found desirable, so long as it is still in a form to allow of its being held gently against the yarn α with a slight counterweight to ensure that it will fall by 25 reason of the counterweight, when the yarn breaks or is removed.

I claim:—

1. In apparatus for the winding of artificial silk yarns in their earlier stages after 30 spinning, a pivotally mounted plate, a curved feeler wire one end of which is attached to the plate at a distance from the pivotal

point thereof, the feeler wire curving above the pivot to the other side of the pivotal point, continuing downwardly on such other 35 side, and curving outwardly towards the yarn being wound, and a contact member on the lower extremity of such curved portion to make feeling contact with the yarn, the pivotal point being substantially central 40 of the plane of movement of the feeler wire and the latter and plate being practically in counterpoise on the pivot.

2. In combination with a plate and feeler wire arranged as claimed in claim 1, a 45 wiper shaft adjacent to the plate, a driving block on the shaft which driving block has an inclined face, a chain sprocket wheel loosely mounted on the shaft and slideable thereon against spring pressure, an inclined 50 face member solid with the sprocket wheel and engaging the inclined face of the driving block, a centrally pivoted lever one end of which engages with the sprocket wheel and its inclined face member to move there- 55 with longitudinally of the wiper shaft, a knock off lever operated by the other and free end of the centrally pivoted lever, and means for driving the wiper shaft through 60 the sprocket wheel and inclined face member which is solid with such sprocket.

In testimony whereof I have hereunto set my hand.

JOSEPH HETHERINGTON STUBBS.
